UNITED STATES PATENT OFFICE.

JOHN L. BOGERT, OF FLUSHING, NEW YORK.

INTERNAL-COMBUSTION HEAT-ENGINE.

No. 927,103.

Specification of Letters Patent.

Patented July 6, 1909.

Application filed April 1, 1905. Serial No. 253,270.

To all whom it may concern:

Be it known that I, JOHN L. BOGERT, a citizen of the United States, residing in Flushing, Queens county, New York, have 5 invented certain new and useful Improvements in Internal-Combustion Heat-Engines, of which the following is a specification.

In internal combustion heat engines utilizing a mixture of hydrocarbon or other vapor 10 or gas and air, which will explode or burn to produce power upon compression, it is well known that the higher the compression pressure before ignition the greater will be the explosion or working pressure, and for every 15 inch of movement of the piston after ignition the quantity of heat turned into work is directly proportional to the pressure during that movement. It is also well known that permanent hydrocarbon gases mixed 20 with air in proper explosive proportions will permit high compression pressures without spontaneous explosion, but in proportion as the hydrocarbon increases in specific gravity it becomes more and more liable to spontaneous 25 explosion when mixed with air and compressed, reducing materially the compression pressure possible in an oil-engine as ordinarily constructed and known to me. Furthermore, as the molecules of a permanent 30 gas mix much more readily with the molecules of air prior to inflammation than do the molecules of a vapor or spray of oil, a mixture of the latter burns more slowly than the former. One of the objections or 35 defects in the use of heavy hydrocarbons for internal combustion heat engines is the ease with which nascent hydrogen is liberated (which takes fire readily when in contact with air) and deposits of carbon are 40 formed upon any metallic surface of a moderate temperature with which the burning mixture comes in contact, such carbon causing the piston to cut the cylinder surface. By using a small proportion of oil to air it has 45 been found possible to get compression pressures of 75 lbs. per sq. inch when the oil (kerosene of commercial quality) is injected into the cylinder on to a hot projection in the compression space, but the proportion of oil 50 is necessarily so small and the mixing of it with air so imperfect that the pressures

generated are relatively very low—usually not more than one-half the pressure generated in first-class gas engines. For this reason, as is well known, oil engines, so 55 called, convert much less of their fuel into work than gas engines.

The object of my invention is to enable any desired compression pressure to be produced in a cylinder and as a consequence to obtain 60 a relatively high explosive pressure, irrespective of the character of the oil or fuel used, provided, of course, it be adapted to produce explosion when mixed with air and properly compressed. 65

To this and other ends my invention comprises the novel details of improvement and arrangement of parts, that will be more fully hereinafter set forth and then pointed out in the claims. 70

Reference is to be had to the accompanying drawings forming part hereof, wherein—

Figure 1 is a vertical cross-section of a two-cycle oil engine embodying my improvements, Fig. 2 is a face view of the cylinder 75 extension liner shown in Fig. 1, Fig. 3 is an end view thereof, Fig. 4 is a detail sectional view of a modification, showing the rearwardly extended portion of the piston having side depressions that serve as ports to 80 permit a scavenging action to the air which flows into the cylinder from the crank case, Fig. 5 is a partly sectional detail view of the oil pump and mechanism for varying the time of delivery of the oil to the cylinder 85 shown in Fig. 1, Fig. 6 is a section on the line 6, 6, in Fig. 5, and Figs. 7 and 8 are sectional views showing modifications of the cylinder, piston, and associated parts, showing the piston in different positions. 90

Similar numerals of reference indicate corresponding parts in the several views.

At 1 is indicated the cylinder shown provided with an extension 1^a, and 1^b indicates what I term a cylinder liner, which serves as 95 the combustion chamber, and 1^c indicates the cylinder head.

2 indicates the piston, 2^b the wrist-pin, 3 the connecting rod, 4 the crank, and 5, 6 the crank case, which may generally be of any 100 well known construction. The piston 2 is provided with a rearwardly extending por-

tion 2° which enters the liner 1^b for compressing the contents of the latter, but the extension 2° does not fit the inner surface of the liner 1^b gas tight, being purposely constructed so that there may be a more or less free fluid passage between them. At 7, in the two-cycle type of engine, is a passage and port to convey the compressed air of the crank case to the cylinder; at 8 is a passage and port to exhaust the spent products of combustion from the cylinder, and at 9 is a passage and port to admit air to the crank case, which details are well known in the art as usually provided in two-cycle engines. 10 While it is customary to provide means for throttling the passage of the contents of the crank case into the cylinder, I have shown a way for giving more or less free admission of air to the crank case, which consists in an 15 adjustable piece or shield 9^b (Fig. 1) having a slot 9^c and held to the cylinder by a screw or screws 9^d, whereby the flow of air through passage 9 may be controlled. But my invention is not limited to this construction as 20 any well known means, such as a valve, may be used to control the admission of air through the passage 9, or through the passage 7.

In the construction shown in Figs. 1, 5 and 30 6 means are shown for pumping fuel to the cylinder and for readily controlling the quantity and time of admission of such fuel. The arrangements I have shown are as follows:—At 10 is a shaft suitably supported by the engine and which may be operated by a gear 10^a meshing with a gear 10^b driven by the crank shaft, and upon shaft 10 is a suitable cam or eccentric 11 which actuates or lifts the piston or plunger 13^a of a pump 13 35 carried by the engine, a roller 12 being shown connected with piston 13^a to be operated by cam 11. The piston 13^a is connected with a lever 13^b, at one end pivotally supported upon the engine, its other end being 40 normally pulled toward cam 11 by a spring 13^c connected with the engine, the downward movement of lever 13^b being restrained by a link 13^d having a slot 13^e receiving a pin 13^f on lever 13^b, the upper end of link 13^d 45 being connected with an arm 13^g pivotally connected with the engine. From pump 13 one or more fuel delivery tubes 14 lead to suitable check valves 14^a, 14^b, from which 50 passages 15 communicate with the interior of the engine, as within the liner 1^b both of which passages, or either one may be used as desired.

In order that the time of delivery of the fuel by pump 13 may be varied at the will of 55 the operator, I have shown means for giving cam or eccentric 11 more or less angular advance while the engine is running, which devices are shown interposed between the cam 11 and the crank shaft. As shown in Figs. 5 and 6 a bevel gear 17 is journaled upon a

70 swinging frame 18 that is mounted upon shaft 10, which, for this purpose, is made in two parts, each part being provided with a bevel gear 17^a meshing with gear 17, whereby as frame 18 is moved angularly about shaft 10 the cam 11 will also be angularly moved about the same center twice as much. At 19 is a slotted link pivoted to the engine and clamped to frame 18 at any desired position of the latter by means of a bolt 20. 75 By this means the cam 11 may be set for operation in any desired angular relation with respect to stroke of the piston or the position of the crank.

Referring now more particularly to the 80 compression or working end of the cylinder and piston, it will be seen that there is a space 1^e between the piston extension 2^o and the cylinder wall, and a constricted space 1^f between the liner 1^b and the cylinder extension 1^a, which spaces are in communication with each other. In Figs. 2 and 3 the liner 1^c is shown ribbed or corrugated on its exterior, whereby the restricted space or spaces 1^f are provided and the liner firmly maintained within the cylinder extension 1^a. Said liner is retained in the cylinder extension 1^c by a flange 1^d which fits in the cylinder head counterbore. In Fig. 1 the piston 2 is shown at the outer end of its stroke, the 90 spent gases being presumed to have escaped from the exhaust port 8 and the slightly compressed air of the crank case to have passed up the passage into the cylinder or the space 1^e. If, now, the cylinder liner 1^b 10 is still entered or closely approached by the piston extension or compressing plunger 2^c, and the latter fits snugly or almost tight to the liner 1^b, then the contents of said liner will be spent gases at or nearly about atmospheric pressure and the contents of the space 1^e and the constricted space 1^f surrounding liner 1^b will be largely air. If oil now be injected through the passage or passages 15 into the liner 1^b no explosion can take place, 110 no matter how high the compression within the liner until enough air is forced into the liner by the piston from the space 1^e around the sides of the piston extension 2^c. Therefore, it will be understood that it will be easy 115 to so proportion the relative diameters of piston 2 and its extension 2° with respect to their compression spaces that the proper amount of air will have entered the liner 1^b just at the inner dead point of the piston, or 120 thereabout. The quantity of air so passing into the liner may be determined by shortening the extension or plunger 2^c with respect to the inner edge of the liner, or by making the fit of the extension or plunger 2^c within the liner sufficiently loose, or by forming longitudinal depressions 2^d on the sides of the extension 2^c (Fig. 4), which will act as 125 passages to permit the ready travel of air from the space 1^e into the liner. Further- 130

more, the quantity of air to be utilized may be reduced by throttling the contents of the crank case either on the suction side or in the passage 7.

5 In addition to using a shield 9^b to control the admission of air to the crank case to prevent enough air entering the liner 1^b to produce an explosive mixture before the inner dead point of the piston is reached, a passage 23 may lead into the cylinder from a closed air chamber 25, which passage will be in such position that the piston may overrun it, and thus it is possible to make this chamber 25 large enough to keep the compression pressures inside the liner 1^b and in the space 1^e the same until the piston 2 overruns the opening of the passage 23 when the compression pressure in the space 1^e will rapidly rise, and thus force air past the plunger 2^e into the liner 1^b to mingle with the mixture there and make it explosive. The volume of chamber 25 may be adjustable in any well known manner. I have shown the same having a cap portion 25^a threaded on a stem or disk 24. The fuel oil may be pumped on the piston extension or plunger 2^e and there mingle with the air rushing into the liner 1^b, or the fuel may be pumped into the liner beyond the piston extension or plunger. The cylinder liner 1^b is introduced within the water jacket for the purpose of keeping the surfaces of the liner hot, but not too hot, a thin film of highly compressed air surrounding the liner in the space 1^f, which air will aid combustion and by its expansion will increase the pressure on the piston, thus turning more heat into work,—heat that otherwise would have passed into the water jacket. It will thus be understood that by means of my improvements the fuel and spent products of combustion with too little air to permit inflammation on the one hand and air on the other may be compressed separately, thus allowing an explosive mixture only when the inner dead point of the compression stroke is reached; or nearly so, for, as the fuel is first injected into the liner containing substantially only spent products of combustion then no explosion will occur no matter how high the temperature of that chamber, or how great the pressure of compression, until the proper quantity of air has been forced into the liner to mingle with the fuel and be compressed therein, and by properly proportioning the parts and spaces the proper quantity of air with relation to the quantity of oil or fuel within the liner may be regulated in order that combustion may take place only at the proper position, or about the dead point of the piston.

In Figs. 7 and 8 are shown cylinder details that embody most completely the ideas hereinbefore set forth, and which relate to the two-cycle type of engine substan-

tially the same as Fig. 1, the pistons being shown in the two extreme positions of their strokes. The cylinder head 1^c is shown constructed with a cylindrical projection constituting what I have termed the liner 1^b, the inner end of which is adapted to nearly fill without touching a relatively deep annular groove or recess 2^e formed in the piston 2 around the extension 2^c. The extension 2^c of the piston may be prolonged to project within the cylindrically shaped head portion of the liner or projection 1^b to any desired extent. While I have shown the projection 2^c so constructed that there is a constricted passage between the inner surface of 1^b and the outer surface of 2^c at all positions of the piston, yet by shortening the extension 2^c a considerable opening may occur between 2^c and 1^b at the extreme forward position of the piston so that as much air as desired from the port 7 may scavenger or wash out the spent products of combustion within 1^b. The peculiar advantages of the space 1^f (Fig. 8) between the extension 2^c and the liner 1^b, as the piston moves within the latter, are that the walls of 2^c and the liner 1^b at the annular space 1^f act as regenerators, transferring the heat to the air that flows from the compression space 1^e into the liner 1^b and at the same time by eddying action preventing the too easy access of air to the combustion space. In Figs. 7 and 8 the cylinder head 1^c is shown inclosing the inner end of liner 1^b in such manner as to form a space 1^h, but I do not contemplate using a water jacket there unless an air jacket, as shown in Fig. 1 is interposed between the walls of the combustion space and the walls of the water jacket. In Figs. 7 and 8 any suitable igniter may be used, though after the engine has run a few minutes the heat of the walls will insure the ignition of almost any combustible mixture of fuel and air, the principal point to be observed being that there shall not be an inflammable mixture within the combustion chamber until the inner dead point of the piston is reached, or thereabout.

In proportion as the speed of the engine increases the lead of the injection of fuel oil into the compression space may be increased, as by means of the devices shown in Figs. 1, 5 and 6, and at all points of the compression stroke, even when the inner dead point is reached, there is, in the case of any of the pistons shown, a violent rush of air into the liner or chamber 1^b, cyclonic in speed and action, and any oil pumped on to the projection 2^c, or even within the combustion space 1^b, will be instantly converted into minute particles. By delivering the oil at the exact inner dead point premature ignition will be impossible, no matter how free the air therein might be from spent products.

nor how hot the containing walls, but by steadily advancing the lead of delivery of the oil a point will be reached where the greatest efficiency will be obtained. In the 5 Diesel engine compression of air to about 500 lbs. per sq. inch is resorted to to obtain heat enough to insure ignition, but in my improvements a much lower pressure will suffice, because of the regenerative action of the 10 combustion space walls and the piston extension 2°, none of which is in contact with water on the other side.

By means of my improvements it will be understood that I am enabled by the stroke 15 of the piston to compress fuel and spent products, and separately compress air, and cause a mingling of such air with the compressed fuel in the proper proportion to cause ignition to take place just at the proper 20 position of the piston and without danger of premature ignition. By reason of the compression of air by the piston to a higher pressure than the compression of the fuel and causing the mingling of the same at the 25 proper time and in the proper proportions is accomplished.

Having now described my invention what I claim is:

1. An internal combustion heat engine 30 having an internal liner constituting the combustion space, and having an air jacket isolating the walls of the liner from the walls of the engine, the engine walls having also inlet and exhaust ports, and a piston arranged to open and close said ports by its movement, substantially as described.

2. An internal combustion heat engine having a water jacket at its combustion end 40 provided with a liner within the combustion end constituting a combustion chamber, and also having an air jacket between the walls of the liner and the walls of the water jacket, the engine walls having also inlet and exhaust ports, and a piston arranged to open 45 and close said ports by its movement, substantially as described.

3. An internal combustion heat engine having a piston provided with an extension, and an air compression space, combined with 50 a liner to receive said extension and constituting a combustion space and means to prevent excess air from entering the liner on the forward stroke of the piston, whereby air compressed by the piston will be forced into 55 the liner past the piston extension on the compression stroke of the piston, the engine walls having also inlet and exhaust ports arranged to be opened and closed by the movement of said piston, substantially as de- 60 scribed.

4. An internal combustion heat engine having a piston provided with an extension and an air compression space, combined with 65 a liner to receive said extension and constituting a combustion space and provided with

means to prevent excess air from entering the liner on the forward stroke of the piston, whereby air compressed by the piston will be forced into the liner past the piston extension on the compression stroke of the piston, 70 and an air jacket between the liner and the engine walls and in communication with said compression space, the engine walls having also inlet and exhaust ports arranged to be opened and closed by the movement of said piston, substantially as described. 75

5. An internal combustion heat engine having a piston provided with an extension and an air compression space, combined with 80 a liner to receive said extension and constituting a combustion space and arranged to prevent excess air from entering the liner on the forward stroke of the piston, whereby air compressed by the piston will be forced into the liner past the piston extension on the 85 compression stroke of the piston, an air jacket between the liner and the engine walls and in communication with said compression space, and means to inject oil into the liner through the wall thereof, the engine walls 90 having also inlet and exhaust ports arranged to be opened and closed by the movement of said piston, substantially as described.

6. An internal combustion heat engine provided with a liner having a space between 95 its outer surface and the engine walls, and a piston provided with an annular recess adapted to receive said liner, the engine walls having also inlet and exhaust ports arranged to be opened and closed by the movement of 100 said piston, substantially as described.

7. An internal combustion heat engine provided with a liner having a space between 105 its outer surface and the engine walls, and a piston provided with an extension and a recess surrounding the same adapted to receive the liner while the extension enters the same, the engine walls having also inlet and exhaust ports arranged to be opened and closed by the movement of 110 said piston, substantially as described.

8. An internal combustion heat engine provided with a liner having a space between 115 its outer surface and the engine walls, and a piston provided with an extension and a recess surrounding the same adapted to receive the liner while the extension enters the same, said recess being of such size that the liner will not touch the piston or its extension 120 when within said recess, the engine walls having also inlet and exhaust ports arranged to be opened and closed by the movement of said piston, substantially as described.

9. An internal combustion heat engine provided with a liner forming a combustion 125 space, the liner having exterior projections forming an air jacket between the liner and the walls of the engine, substantially as de- 130 scribed.

10. An internal combustion heat engine 130

having a combustion space and a piston provided with an extension to enter said space and an air compression space partly isolated from the compression space by said extension, the space between the extension and the combustion space serving to regulate the admission of air into the combustion space from said compression space, the engine walls

having also inlet and exhaust ports arranged to be opened and closed by the movement of 10 said piston, substantially as described.
